UNITED STATES PATENT OFFICE.

FRANK H. HOUGHLAND, OF CINCINNATI, OHIO.

FOLDING BOX.

1,200,840.

Specification of Letters Patent. Patented Oct. 10, 1916.

Application filed April 12, 1916. Serial No. 90,701.

To all whom it may concern:

Be it known that I, FRANK H. HOUGHLAND, a citizen of the United States, residing at Cincinnati, in the county of Hamilton and State of Ohio, have invented certain useful Improvements in Folding Boxes, of which the following is a specification, reference being had therein to the accompanying drawing.

10 This invention relates to improvements in folding boxes, one object of the invention being the provision of a tray box in which the ends and side walls are permanently connected together in such a manner as to permit of said walls when collapsed to lie in the same plane and which will permit the easy extension of said walls and the locking thereof in extended position without the insertion of tongues as is the usual practice.

20 A still further object of this invention is the provision of a box of this type in which the end walls, carry a reinforcing flap which in turn coöperates with extensions carried by the side walls so that such members may be stapled or permanently fastened to the end walls and at the same time permit of the collapsing of the tray so that the end walls will be moved outwardly and the side walls moved inwardly and at the same time 25 not interfere with the connecting members of the walls.

30 A still further object of this invention is the provision of a box of this character which is simple, durable and inexpensive in 35 construction and which is thoroughly efficient and practical in use.

In the accompanying drawings: Figure 1 is a plan view of a blank of one end of the tray. Fig. 2 is a similar view showing the 40 ends attached and in collapsed position. Fig. 3 is a perspective view showing the tray extended. Fig. 4 is a section through the edge flap of the end wall and adjacent parts. Figs. 5 and 6 are views in blank of modified 45 forms.

Referring to the drawings, the numeral 10 designates the bottom of the box and 11 the two side walls thereof, the end wall 12 being connected permanently to the bottom and 50 side walls through the instrumentality of the two triangular connected members 13 and 14 which are provided with the diagonal fold 15 and slit 16. Carried by the member 14 is an extension 17 whose base is a fold 55 line 18 which with the fold 15 and the slit 16 forms a diagonal at the corner of the box.

When the side walls and end walls are connected, the extensions 17 are folded to be co-extensive with the inner wall of the end, while the flap 19 upon the upper edge 60 of the end wall is folded inwardly and is secured to the end wall and the respective extensions 17 by means of two staples 20. In this manner the side walls of the box may be extended inwardly when collapsed, while the end walls are extended outwardly, the flap 19 and the extensions 17 remaining in such stapled position at all times.

Carried by the flap 19 is an extension terminal flap 21 having the curved edges 22, the flap 19 being of sufficient length to extend within the box when the tray is extended and having its short edges 19' engage the side walls while the extension flap or locking member 21 is folded under and upwardly to 75 engage the end wall between such end wall and the extension 17. Thus the flap 21 operates and is locked to hold the flap 19 flat and the ends braced against collapsing.

In Fig. 5, the corner flap 13'' is cut to 80 provide the flap 23, which forms a part of the flap 17, the same being folded to assume the position shown at the left.

In Fig. 6, the corner flap 13' carried the 85 extensions 17'', while an additional securing flap 24 is carried thereby, staples 25 being provided to connect the flap 24 to the end of the box, the end of the box being formed similar to the other construction heretofore set forth. This construction provides an exceedingly rigid box for a deep box in that instead of being secured by staples as in other forms, the additional staples 25 and securing flaps 24 are provided.

What I claim as new is:—

1. A folding box comprising a blank having bottom, side and end walls, a diagonally folded connection between the side and end walls, an extension on each connection and meeting the diagonal fold thereof, an end flap of the same length as each end wall and carried thereby and adapted to be folded inwardly and upon said extensions, fastening devices for connecting the end flaps, and extensions to the end walls, and a locking flap carried by each end flap interpositioned between the extension and the end wall adjacent thereto whereby the box is locked in its extended position.

2. A folding box comprising bottom, side and end walls, foldable corner pieces connecting the side and end walls, extensions carried

by the corner pieces and protruding from the folds thereof, said extensions being adapted to be in the same plane, foldable end flaps on the end walls and engageable with the extensions, means for connecting the end flaps and extensions to the end walls, and means on the end flaps for interposition between the extensions and the end walls.

3. A folding box comprising bottom, side 10 and end walls, foldable corner pieces connecting the side and end walls, extensions carried by the corner pieces and protruding

from the folds thereof, said extensions being adapted to be in the same plane, foldable end flaps on the end walls and engageable with the extensions, means for connecting the end flaps and extensions to the end walls, and means on the end flaps for interposition between the extensions and the end walls, said extensions being foldable to be co-extensive 15 with the inner surfaces of the end walls. 20

In testimony whereof I affix my signature.

FRANK H. HOUGHLAND.
